UNITED STATES PATENT OFFICE.

WILLIAM A. CHAMBERLAIN, OF SUNBURY, PENNSYLVANIA.

ELECTRICALLY-OPERATED PHOTOGRAPHIC APPARATUS.

No. 889,659.

Specification of Letters Patent.

Patented June 2, 1908.

Application filed January 25, 1906. Serial No. 297,849.

To all whom it may concern:

Be it known that I, WILLIAM A. CHAMBERLAIN, a citizen of the United States, residing at Sunbury, in the county of Northumberland, State of Pennsylvania, have invented certain new and useful Improvements in Electrically-Operated Photographic Apparatus; and I do hereby declare the following to be a full, clear, and exact description of the invention, such as will enable others skilled in the art to which it appertains to make and use the same.

This invention relates to electrically operated photographic apparatus and contemplates means for simultaneously operating a camera shutter and a flash-light mechanism.

The invention is intended for use in banks, houses and the like to obtain a photograph of a burglar attempting to enter the bank or house and is adapted to be automatically operated by the raising of a window or the opening of a door, or by any other desired means.

In the accompanying drawings: Figure 1 is a view, partly in section, of the device in use, showing the relative arrangement of parts. Fig. 2 is a detail bottom plan view of the electro-magnet and its associated parts.

Referring to the drawings, 5 denotes a base, preferably of wood, to which is secured, in any suitable manner, a base-plate 6 carrying an electro-magnet 7 of the usual construction.

Formed on the base-plate 6 are oppositely disposed lugs 8, provided with eyes 9 in which are engaged the reduced ends 10 of an armature 11. Secured at its lower end to the armature 11 is a contact-rod 12 which is passed through a slotted guide-lug 13 on the base 5. A valve-rod 14 is pivoted at its lower end to the armature 11, is preferably of non-conducting material, and is passed through a guide 14' carried by the base-plate 6, and the valve-rod 14 is connected to a valve-arm 15 which controls a valve 16 located in a pipe 17 which leads to an acetylene gas-generator 18 located at any desired point adjacent the base 5.

The generator 18 comprises a tank 19 provided with a cover 20 which is securely held on said tank 19 by means of a threaded rod 21 which is secured to the cover 20 and extends downwardly to the bottom of the tank 19 and is provided with a thumb-nut 22. A rubber gasket is disposed in an annular groove 23 in the upper edge of the tank 19 to

prevent leakage of the gas from the generator. Secured to the bottom of the tank 19 and extending upwardly therefrom and surrounding the rod 21 is a tube 24 which prevents contact of the carbide with the said rod 21. A reservoir 25 is provided with a pipe 26 which extends into the tank 19 and terminates adjacent the bottom of the same.

A contact-rod 27 is secured to one of the coils of the electro-magnet 7 and has its upper end turned to lie above the contact-rod 12 and in contact therewith.

Disposed above the upper ends of the contact-rods 12 and 27 and the pipe 17 is a foraminous plate 28 which is designed to hold a suitable quantity of flash powder and partially surrounding the said plate is a hood 29 which serves the dual purpose of a reflector and a shield to prevent the flame from the flash setting fire to adjacent woodwork, etc.

Secured to the armature 11 at one side of the bottom thereof and projecting laterally from the same is a trip-finger 30 which is located in the path of and adapted to be engaged under a lug 31 formed on a sliding camera-shutter 32. The shutter 32 is slideable vertically in a shutter casing 33 and is provided with an elongated opening 34 which registers with an opening 35 in the shutter casing 33 when the shutter 32 is at the limit of its downward movement in the said shutter casing, which forms a portion of a camera 36.

A leaf spring 37 is secured to the under side of the armature 11 and against the free end of the spring is adapted to seat a setscrew 38 carried by an arm 39 on the base 5 below the armature 11, to permit of adjustment of the armature with relation to the electro-magnet.

Conductor wires 40 lead to binding posts 41 on the base 5 and connected to the said binding posts are other conductor wires 42 which lead to any suitable circuit closer located in any desired place.

Should the circuit become closed by the raising of a window, the opening of a door, or in any other manner, the armature will be attracted to the electro-magnet as will be readily understood. This will cause the contact-rod 12 to move away from the rod 27 thereby breaking the circuit and causing a spark and at the same time, the valve 16 will be opened by the valve-rod 14 and the trip-finger 30 will be swung not only upwardly but also forwardly to such a degree that it

- will be released from the lug 31 on the shutter 32 thereby allowing the same to drop, it being understood that the spark ignites the gas issuing from the pipe 17 and hence igniting the flash powder on the foraminous plate 28.
- 5 The electrical circuit enters through one of the wires 40 and passes through the electro-magnets and out through the other wire 40, it being understood that this energization of the magnets will serve to attract the armature and that when the armature is so attracted, it being in circuit with the plates 6 upon which the coils are arranged, the arm 12 will be swung out of contact with the arm 15 27 and hence the circuit will be broken and a spark will result. The armature then drops to its original position and the circuit is again made through the armature, the arms 12 and 27, and the coils. It will further be understood that the circuit will be made and broken repeatedly and that hence a number of sparks will result, thereby insuring proper 20 operation of the device.

The circuit through the device is through 25 one of the wires 40, through the coils, thence through the contact arm 37, which is in circuit with one of the coils, afterwards through the movable contact arm 12, and through the armature 11, the base plate 6, and out through 30 the other wire 40, this circuit being rapidly made and broken so as to produce sparks of rapid succession beneath the plate 28.

What I claim, is:—

1. In a device of the character described 35 the combination with an electric magnet and its armature, a camera shutter, and a valve, of means for simultaneously operating the shutter and the valve.
2. In a device of the character described 40 the combination with an electro magnet and its armature, a camera shutter, a valve, and a sparking device, of means for simultaneously operating the shutter, valve and sparking device.
- 15 3. In a device of the character described the combination with an electro magnet and its armature, of a gas supply pipe, a valve interposed in the pipe, a sparking device, a camera shutter, connections between the 50 valve and the armature for opening the former, and means for operating the sparking device and the shutter simultaneously with the opening of said valve.
4. In a device of the character described

the combination with an electro magnet and 55 its armature, of a camera shutter, a sparking device and a valve, connection between said shutter and said armature for opening the former, and means for operating the sparking device and the valve simultaneously with 60 the opening of the shutter.

5. In a device of the character described, the combination with an electro-magnet and its armature, of a contact member associated with said electro-magnet, a second contact 65 member associated with said armature, a fuel supply valve, connections between said valve and said armature for operating the former, a powder receptacle, a camera-shutter, and means associated with said armature 70 for releasing said shutter.

6. In a device of the class described the combination with an electro-magnet and its armature, of a gas supply valve, a rod connecting said valve and said armature for opening the former when the latter is moved, a contact arm carried by one of the coils of the electro-magnet and in circuit therewith and extending to a point adjacent the outlet of the valve, a contact arm carried by the armature and lying normally in contact with the last named arm and arranged for movement out of contact therewith when the armature is attracted to its magnet, and means connected with the armature for releasing the camera 85 shutter.

7. In a device of the class described the combination with an electro-magnet, an armature for the magnet and a camera having a drop shutter, of a gas supply valve, a 90 rod connecting the valve and armature for opening the former when the latter is moved, a contact member in circuit with one of the coils of the magnet, a second contact member carried by the armature and lying normally in engagement with the first named contact member, and an arm carried by the armature and arranged to support the camera shutter, said arm being released from such engagement with the shutter when the armature is moved.

In testimony whereof, I affix my signature, in presence of two witnesses.

WILLIAM A. CHAMBERLAIN.
